ABSTRACT

A quick-release cam lock for selectively locking the relative position of a hydraulic cylinder and a piston. The quick-release cam lock permits speedy unlocking and repositioning of the hydraulic cylinder and its accompanying piston and oversleeve, thus allowing for speed in repositioning, assembly or disassembly while also providing a secure positive positioning lock between the hydraulic cylinder, piston and oversleeve while the quick-release cam lock is engaged.

FIG. 7

QUICK-RELEASE CAM LOCK**FIELD OF THE INVENTION**

The present invention relates generally to devices for protecting workers doing any type of work in excavations such as below ground repairs, maintenance or installation of any type such as trenching, bore pits, manhole installations, or pipe line maintenance work. More particularly this invention relates to a new and improved way for locking or fixing the position of hydraulic cylinders used in the trench shoring industry and elsewhere hydraulic cylinders in general.

BACKGROUND OF THE INVENTION

Presently available excavating equipment permits digging rapidly so that excavation work can be done and the excavation immediately filled. However, installations which require personnel to enter into the excavation (which can be rather deep and through unstable soil) have the potential for cave-ins. Such cave-ins of the excavation not only interfere with the maintenance or construction operations, but also may cause serious injury or even loss of life to working personnel. There are various types of devices at this time in the field which are utilized in these maintenance and construction trenches or excavation shoring operations to support be placed against the walls of the excavation. Samples of shoring devices generally known in the field include shoring shields, skeleton boxes, waler, vertical shores, and four-way manhole braces.

The various types of shoring devices generally incorporate hydraulic cylinder arrangements which are used for shoring the sides of trenches or excavations. It is common for devices such as these to utilize one or more horizontally disposed vertically spaced hydraulic cylinder/piston units that are connected at their opposite ends to shoring rails which extend vertically and which will be held against the opposite sides of the trench when the hydraulic cylinder/piston units are expanded. Another common shoring device uses one or more horizontally disposed, horizontally spaced, hydraulic cylinder and piston units connected pivotally at their opposite ends to horizontal shoring rails which butt against the excavation walls, shoring timbers or sheeting which may be vertically disposed at the opposite sides of the trench. Each of these types of shoring devices operate so that the cylinder and piston units act as cross-braces extending across the trench. Once the shoring devices are inserted into the trench, hydraulic fluid is pumped into the cylinders to force the pistons to extend and thereby to jack the shoring rails apart to the desired extent, and thereby hold the shoring rails or shoring boards tightly against the opposite walls of the trench to prevent sloughing of the material behind the boards or to prevent such dangers as cave-ins. Often, oversleeves are placed so as to surround and cover the piston to protect it from dirt and the like. The oversleeve slides over the cylinder when the hydraulic piston is retracted and extends with the piston exposing the cylinder.

Currently, there exists various types of hydraulic jacking units which are provided with assorted positive supporting mechanisms to lock the jack into extended position and to fix the relative position of the piston and cylinder units so as to prevent retraction of the piston into the cylinder even in the event of pressure loss or release from the cylinder. Such devices generally utilize either a pin, as disclosed in U.S. Pat. No. 4,682,914 to Aihara; 3,224,201 to Brunton; 3,851,856 to Berg; and U.K. Patent No. 2,095,719, or a threaded piston with a locking screw, as disclosed in U.S. Pat. No. 3,905,279 to Yadon; 4,787,781 to Bradberry; 3,766,740 to

Teegan; 4,449,734 to Cory; 3,321,182 to Elenberg; 4,247,082 to Sjolund and Japanese Patent No. 1,459,090.

Unfortunately, the above referenced devices generally fail to provide for rapid and simple operator activation positioning and engagement during set up, operation, and breakdown of the shoring device and additionally fail to provide for the flexibility of linear locking. Further, the prior art devices often allow for exposed threads, where threads are used, as part of the positioning or locking mechanism utilized with the shoring device, such threads being easily damaged and clogged with dirt, concrete or other foreign matter which is often utilized in conjunction with trenching operations. Still further, these devices can be properly locked only after the device is in the trench, whereas the present invention provides the alternative of linear locking prior to placing the shoring device or hydraulic cylinder into a trench or other end use location.

Accordingly, the quick-release cam lock of the present invention provides a means for quickly and easily locking a hydraulic cylinder/piston arrangement at any desired width by means of a positive locking cam mechanism while also providing for a quick-release mechanism for ease of operability during repositioning of the hydraulic cylinder/piston arrangement. Notwithstanding the various devices referred to above, various other problems associated with devices for preventing the retraction of the piston into the cylinder, even in the event of pressure loss or release from the cylinder, are solved in the new and improved quick-release cam lock for hydraulic cylinders of the present invention.

SUMMARY OF THE INVENTION

The present invention provides a mechanism to positively locks relative positions of a hydraulic cylinder and its piston in a shoring device and to prevent collapse in the event of a hydraulic cylinder failure or leakage. Additionally, the present invention provides a means for quickly releasing such locking mechanism to allow for a speedy readjustment of the relative position of the hydraulic cylinder to the piston. Generally, the locking mechanism mounts to the oversleeve slidably mounted over the hydraulic cylinder/piston arrangement. The oversleeve actually moves over the cylinder simultaneously with the hydraulic piston as the piston moves into and out of the cylinder. The locking mechanism locks by engaging a camming means against the hydraulic cylinder preventing retraction but allowing expansion. Basic set up for the present invention provides that the preferred embodiment be mounted at one end of a hydraulic piston/cylinder oversleeve. Mounting is preferably accomplished by utilizing one or more cone headed locking screws which once engaged do not extend any further than the outside edge of the body of the present invention. Hydraulic fluid moves the piston head which in turn moves the piston and oversleeve/locking mechanism arrangement since they are all affixed. Consequently, when the locking mechanism engages it is always immediately outside of the hydraulic cylinder from the piston head. This arrangement allows the piston head to provide a support in opposition to the locking mechanism and more particularly the camming means so that the hydraulic cylinder is not distorted or crushed when the cam is engaged.

A significant advantage of the present invention is that it allows for simple control of the engagement and disengagement of the locking mechanism, thus allowing for quick setup, repositioning, or breakdown of a shoring device while also providing a positive lock to the position of the hydraulic cylinder in relation to its piston to insure against possible

collapse of the shoring device. A further advantage of the present invention is that it allows the locking device to be in either an engaged position, a disengaged position; or released intermediate position in which movement is permitted linearly in one direction but is restricted in the other direction.

These and other features and advantages of the present invention will be more readily apparent and more fully appreciated upon reading the following description of a preferred exemplified embodiment to the invention and upon reference to the accompanying drawings herein.

BRIEF DESCRIPTION OF THE DRAWINGS

FIG. 1 is a perspective view showing the quick-release cam lock of the present invention mounted against a hydraulic oversleeve;

FIG. 2. is a cross-sectional view of the quick-release cam lock and hydraulic oversleeve of FIG. 1;

FIG. 3. is a cross-sectional view of the present invention illustrating the cam in a "disengaged" position for receiving a hydraulic cylinder;

FIG. 4 is a cross-sectional view of the present invention displaying the coil spring and cam arrangement, showing the cam in its "disengaged" position;

FIG. 5 is a cross-sectional view of the present invention, similar to FIG. 3, showing the cam in a "released" position and engaging the piston;

FIG. 6 is a cross-sectional view of the present invention showing the coil spring and cam of the quick-release cam lock in the "released" position;

FIG. 7 is a plan view showing the quick-release cam lock mounted on a hydraulic oversleeve and engaging the surface of a hydraulic cylinder;

FIG. 8 is a facial plan view showing the quick-release cam lock.

While the invention will be described and disclosed in connection with certain preferred embodiments and procedures, it is not intended to limit the invention to those specific embodiments, rather it is intended to cover all such alternative embodiments and modifications as falls in the spirit and scope of the invention.

DETAILED DESCRIPTION OF THE PREFERRED EMBODIMENT

The preferred embodiment of the present invention is shown in FIG. 1 through FIG. 8, wherein the quick-release cam lock is displayed in different positions relative to a hydraulic oversleeve and cylinder.

The quick-release cam lock includes a extruded substantially tubular body 1 having a substantially cylindrical section 3, a substantially rectangular housing of section 5, a substantially planer mounting face 7, and a substantially planer back face 9. The tubular body 1 may rest or ride on a hydraulic cylinder 100 and may be demountably coupled to a hydraulic oversleeve 105 by means of at least one, a plurality in the present invention, cone headed locking screws 11 in the tubular body 1. A threaded channel 14 is depicted and corresponds to the screw 11. The locking screws 11 contain threads 12 which threadably engage threaded channel 14 which is designed to receive said screw 11. The end portion 16 of locking screws 11 may engage the hydraulic oversleeve 105 at 18 and preferably are of the recessed Allen type.

In order to perform its described functions, the quick-release cam lock of the present invention has a cam 20 with

a camming surface 21, said camming surface containing a plurality of teeth 22. The cam 20 is pivotally mounted within a slot 24 centered in the rectangular housing section 5 of tubular body 1. The cam 20 is pivotally mounted on a high-strength shaft 26 which extends through the tubular body 1. The pivotable mounting is accomplished by extending the cam shaft 26 through cylindrical opening 25 within the cam 20. Cam 20 is substantially triangular as shown with the camming surface 21 located along the hypotenuse in a semi-circular arrangement. Preferably the shaft 26 will be set into and threadably engage the tubular body 1 by means of a recessed screw bolt 28 as shown in FIG. 4. The recessed screw bolt 28 contains a head 29 which rests within a corresponding recess 31 in the housing section 5 of tubular body 1. Extending from said head portion 29 is shaft 26 which contains threads 33 and a portion of the shaft 26 opposite screw bolt head 29. The threads 33 engage the threaded channel 35 for within the portion of rectangular housing section 5 opposite channel 24 designed to receive the threads of 33 of recessed screw bolt 28.

Also mounted about the shaft 26 is a biasing means such as a coil spring 30 which is set in a recessed portion 10 of the tubular body 1 and engages at one end 36 the tubular body 1 and at the other end 37 the cam 20. The coil spring 30 provides rotatable tension on the cam 20 so that the cam 20 selectively engages the cylinder 100. This is accomplished by the engagement of spring end 37 against cam abutment pad 39 which is integrally attached to cam 20.

To provide a two-position selectively engageable and releasable locking mechanism, the cam is provided with an integrally formed tail 21 which may selectively either pass through or engage the locking pin 40. The locking pin 40 passes through by virtue of aperture 41 and is slightly longer than the rectangular section 5 of the tubular body 1. The locking pin 40 extends through a portion of channel 24. Locking washers 2 are fixably mounted on each longitudinal end of the locking pin 40 and the locking pin 40 includes a radial groove 44 through which the tail 21 of the cam 20 may pass when the locking pin 40 is in its released position as shown in FIG. 5. A slit 99 is also provided in the bottom of the channel 24 of the tubular body 1 so as to provide clearance for the tail 21 of the cam 20.

As discussed briefly above, hydraulic cylinder and piston arrangements are generally fitted with an oversleeve. The oversleeve such as the one depicted herein as 105, is able to slide over and encompass the hydraulic cylinder 100. The oversleeve 105 moves in concert with the hydraulic piston (not shown). That is, the hydraulic piston, or any portion thereof which extends out of the cylinder 100, is always 50 protected by the hydraulic oversleeve 105. When the piston is fully retracted within the hydraulic cylinder 100, the oversleeve 105 encompasses more of the surface area of the hydraulic cylinder than at any other time. As the piston is hydraulically motivated to extend out of the cylinder 100, 55 the oversleeve 105 maintains its protective covering of the piston, sliding over the hydraulic cylinder 105 and exposing more of the surface area of said hydraulic cylinder 100 as the piston extends. When the piston is retracted, the hydraulic oversleeve 105 is once again pulled over the hydraulic cylinder 100. This prevents dirt and other foreign matter 60 from resting on the hydraulic piston and then being drawn into the hydraulic cylinder when the piston is retracted.

As shown in the drawings, the cam 20 may either be in an "engaged" position wherein the locking pin is in a "closed" position, a "disengaged" position, as shown in FIG. 3, wherein the locking pin 40 is in a closed position preventing the engagement of the cam 20 with the hydraulic cylinder

100, or in a engaged position as shown in FIG. 5, wherein the locking pin 40 is in a "open" position so that the tail 21 of the cam 20 aligns with and passes through the radial groove 44 in the locking pin 40. In the "engaged" position, the locking pin 40 will prevent movement of the cam 20 beyond the point wherein the teeth 22 of the cam engage the hydraulic cylinder 100. The teeth are designed so as to angle into the hydraulic cylinder 100. That is, teeth 22 are angled such that linear movement of the hydraulic cylinder 100 out of said oversleeve 105 will be readily tolerated but linear movement of the cylinder 100 into said oversleeve 105 will cause the teeth 22 to positively engage cylinder 100, preventing any further such movement. This will lock the cam onto the cylinder 100 and prevent any movement of the cylinder 100 in relation to the hydraulic oversleeve 105 on the hydraulic piston.

In the "disengaged" position shown in FIG. 3, the locking pin 40 is in its "closed" position so that the locking pin 40 prevents the teeth 22 of the cam 20 from engaging the cylinder 100. In this position, the quick-release cam lock may freely slide linearly in either direction along the hydraulic cylinder 100. In the "released" position shown in FIG. 6, the radial groove 44 of the locking pin 40 aligns with the tail 21 of the cam 20. The coil spring 30 is biased so that in such a position, the spring 30 provides tension so as to rotate the cam 20 so that teeth 22 engage the cylinder 100. This spring actuated engagement freely allows linear movement of the quick-release cam lock or the hydraulic cylinder 100 in one direction while restricting movement in the direction of compression of the hydraulic cylinder/piston arrangement. FIGS. 3 and 5 disclose more specifically the piston head arrangement. Generally, the piston head is comprised of a number of parts which in turn are affixed to piston rod 150. Here a mandrel 156 is threadably engaged to piston 150 by virtue of an extended threaded shaft 154 which corresponds to threaded receptacle 152. A seal guide 167 is threadably mounted to the piston head mandrel 156 by virtue of a number of elements including bolt 166, washers 162 and 164. Bolt 166 is threadably engaged to the mandrel 156 by virtue of threads 160 received in threaded mandrel conduit 158. The piston head seal guide 167 preferably incorporates a pliable seal 170.

In the preferred embodiment of the invention, the tubular body 1 is made of a metal such as aluminum and is generally machined to provide a relatively smooth surface. Such other parts as described above preferably may be made of a 45 hardened steel of types generally known in the field. An inwardly offset annular lip 110 is located just inside of mounting face 7 and corresponds to and receives the oversleeve slip 112. The locking screws 11 pass through the tubular body 1 and engage the oversleeve lip 112 as it rests on annular lip 110. This provides for the mounting engagement of the present invention to a hydraulic cylinder/piston arrangement.

As is apparent from the foregoing description, the present invention provides a locking mechanism for securely fixing the relative position of a hydraulic cylinder and piston. Obvious modifications will occur to those skilled in the art without departing from the scope of the invention, and as such the invention is not to be limited to the specific preferred embodiment claimed herein. While the present invention has been described most specifically as being used as a locking mechanism in a hydraulic cylinder and piston type arrangement, it is clear that possible other embodiments of the quick-release cam lock could be used for securely positioning two tubular members of any sort and the foregoing disclosure is in no way meant to limit such potential uses.

What is claimed is:

1. A quick-release cam lock arrangement comprising:
a hydraulic oversleeve;
a substantially tubular body having a slotted portion releasably mounted on said oversleeve;
a camming means for preventing undesired movement through said tubular body, pivotably attached to said tubular body within said slotted portion of said tubular body; and,
a locking means for selectively locking said camming means against movement relative to said tubular body.
2. The quick-release cam lock of claim 1 wherein said camming means includes a cam having a plurality of grooved teeth.
3. The quick-release cam lock of claim 1 wherein said locking means is a locking pin.
4. The quick-release cam lock of claim 1 further comprising a biasing means for selectively activating said camming means.
5. The quick-release cam lock of claim 4 wherein said biasing means is a coil spring, said coil spring having a first end proximate said tubular body and a second end proximate said camming means.
6. The quick-release camlock of claim 1 further comprising at least one locking screw, said locking screw matably engageable to said tubular body for mounting said camlock to a tubular or other suitable item.
7. The quick-release cam lock of claim 6 wherein said locking screws selectively engage a hydraulic cylinder.
8. The quick-release camlock of claim 1 wherein said locking means is a locking pin and said camming means has a tail and said locking pin has a groove such that said tail of said cam is selectively engageable with said groove of said locking pin.
9. A quick-release camlock comprising:
a substantially tubular body having a slotted portion;
a cam having grooved teeth, said cam rotatably attached to said tubular body within said slotted portion of said tubular body;
a coil spring for biasing said camming means in an activated position having a first end proximate said tubular body and a second end proximate said cam; and,
at least one locking screw passing through and threadably engaged to said tubular body for mounting said camlock to a tubular hydraulic oversleeve or other suitable item.
10. The quick-release cam lock of claim 9 further comprising a locking means for selectively locking said cam.
11. A quick-release camlock for hydraulic cylinders/piston apparatus comprising:
a hydraulic cylinder;
an oversleeve slidably mounted over said hydraulic cylinder;
a substantially tubular body releasably mounted on said oversleeve, said body having a slotted portion;
a camming means for preventing undesired movement through said tubular body, pivotably mounted to said tubular body within said slotted portion;
a locking means for selectively locking said camming means against movement relative to said tubular body.

12. The quick-release cam lock of claim 11 wherein said camming means further comprises grooved teeth mounted thereon, such that said teeth can directly engage said hydraulic cylinder and any retraction of said cylinder into said oversleeve causes said camming means to more firmly engage said cylinder while still allowing extension of said cylinder without interference.

13. The quick-release cam lock of claim 11 further comprising a biasing means for said camming means maintaining said cam in direct contact with said hydraulic cylinder unless prevented by said locking means.

14. The quick-release cam lock of claim 11 wherein said biasing means is a coil spring having a first end proximate said tubular body and a second end proximate said cam.

15. The quick-release cam lock of claim 11 wherein said releasably mounted tubular body comprises at least one locking screw passing through and threadably engaged with said tubular body.
